UNITED STATES PATENT OFFICE

FRANK F. SCHMIEGE, OF KALAMAZOO, MICHIGAN

APPARATUS FOR PRODUCING WOVEN WIRE CLOTH

Application filed July 11, 1931. Serial No. 550,220.

This invention relates to improvements in apparatus for producing woven wire cloth, and more particularly to an attachment for a standard wire weaving loom which will permit the use of a shute or filler wire heavier in proportion to the size of the warp wire in the manufacture of the woven cloth.

In the use of a standard wire weaving loom, it is the customary practice to run the upper and lower sheds of the warp wire through a slay which drives the shute or filler wire into its proper position with respect to the warp wire. Cloth woven in accordance with standard practice then passes over the breast beam 15 to a take-up or cloth roll upon which it is collected.

It has been found difficult to produce perfectly smooth cloth without a wavy surface, and in order to accomplish such result, it is necessary to crimp each shute wire to a certain extent and as the size of the shute wire is increased in proportion to the warp wire, it becomes increasingly difficult to crimp the shute wire sufficiently to prevent the formation of a wavy cloth. For example, when .007 inch warp wire is used in the production of cloth on a standard loom it is difficult to employ a .00775 inch filler wire without the formation of a wavy cloth, although the difference in the size of the warp and shute wires is very slight.

The advantages of providing a cloth of very smooth surface wherein the shute wire is of greater diameter than the warp wire, have been long recognized, the use of such cloth being particularly advantageous in making the belts of paper machines and the like, due to the additional wearing surface provided on the warp wire and the added rigidity of the cloth, as well as to the more efficient draining action provided.

Attempts have been made to overcome the difficulties incident to the use of standard looms and to provide wire cloth of the character referred to and while more or less indifferent success has been attained, attachments ordinarily provided for this purpose have been found to be subject to excessive wear, which wear in turn roughens the woven cloth. 50 Such attempts have embodied the use of rela-

tively rigid rods or bars carried by and movable with the slay to slightly elevate the cloth adjacent the weaving point, since such elevation of the cloth permits the production of cloth which will be free from wavy surfaces even when relatively large shute wire is employed. As stated, however, practical difficulties have been encountered with such constructions such as the excess wearing of the elevating bar or rod, which wearing produces rough surfaces having a substantial abrading effect upon the cloth.

An important object of the present invention is to provide a novel and fully practicable attachment for a standard wire weaving loom which will permit the production of wire cloth having a particularly smooth, even surface.

A further object is to provide an attachment of the character referred to which permits the production of a smooth wire cloth wherein the shute or filler wire is of substantially larger diameter than the warp wire.

A further object is to provide an attachment of the character referred to which presents a relatively great area to the lower surface of the cloth, and which is resilient in its action, thus substantially eliminating wear upon the attachment together with the disadvantages incident thereto.

A further object is to provide stationary mounting means for the attachment to eliminate the necessity of securing the attachment to the slay to move therewith.

Other objects and advantages of the invention will become apparent during the course of the following description.

In the drawings I have shown one embodiment of the invention. In this showing,

Figure 1 is a side elevation of a standard loom showing the attachment in operative position,

Figure 2 is an enlarged detail perspective view of one of the supporting devices for the attachment,

Figure 3 is an enlarged front elevation of a portion of the slay and associated elements, parts being shown in section, and,

Figure 4 is an enlarged fragmentary sectional view through the breast beam and as-

sociated elements, showing the invention applied.

Referring to the drawings, the numeral 10 designates a standard wire weaving loom as a whole having a pair of side frame members 11 suitably connected together in the usual manner. The side members extend upwardly forming a support 12, above the bed of the loom, adapted to pivotally support a slay 13 of the standard type indicated by the numeral 13.

Warp wires 14 are fed from a back beam 15 and pass over the usual guide bar 16. Suitable heddles 17 are arranged in the path 15 of the warp wire beyond the guide bar 16, and from the heddles, the wire passes through the lower portion of the slay in the usual manner. As is well known, the slay serves to drive the filler wire into proper position, as 20 the warp wire passes therethrough to form the woven cloth. The slay carries the usual reed 16' held in position by a steel bar 17'. After leaving the slay, the woven cloth passes over a breast beam 18 to a take-up roll 19.

25 The parts previously described are all elements of a standard wire weaving loom, and any suitable means of the usual type may be employed for swinging the slay back and forth to drive the shute wire into position, 30 and for operating the other standard parts of the loom which form no part of the present invention.

The device forming the subject matter of 35 the present invention comprises a plurality of base plates 20 arranged at any suitable distance apart in a longitudinal recess 21 formed in the breast beam 18. In practice, the plates 20 are preferably arranged about eighteen inches apart, and are provided with 40 opposite outstanding flanges 21 receiving bolts 22 by means of which the plate is secured in the position indicated. A supporting bracket 23 is arranged on the elevated central portion of each plate 20, and may be 45 spaced therefrom by suitable shims 24. Each bracket includes outstanding flanges 25 bolted to the base plate as at 26. Each bracket further includes a central vertical flange 27 having a preferably integral top 28 extending transversely of the flange and longitudinally with respect to the breast beam. Each 50 foot 28 is provided with a bolt receiving opening 29 for a purpose to be described.

A relatively heavy longitudinal plate 30 55 is bolted to the foot 28 of each bracket 23 by a bolt or screw 31 mounted in the opening 29 of each foot 28. Above the plate 30 is arranged a second plate 32 bolted to the first plate as at 33 and extending throughout the 60 length thereof. The plate 32 is fairly heavy, and is held rigidly in position by the plate 30 as will be apparent. The elevation of the plate 32 to the position shown in Figure 4 provides sufficient clearance for the shuttle race 65 (not shown). The broken line 34 indicates

the normal plane of travel of the cloth, and it will be apparent that the body of the plate 32 is inclined with respect thereto. The top of the plate 32 adjacent its free end, however, is provided with a tapered face parallel to 70 the plane 34 of the cloth.

A resilient contact member 35 is arranged over the plate 32 and contacts with the tapered face thereof. The contact member is preferably made of spring steel of about .014 75 gage and extends throughout the length of the plate 32 and projects beyond the free edge thereof, as shown in Figure 4, to support and elevate the wire cloth up to the last shute wire driven into position. Leaf springs or 80 spring steel arms 36 are brazed or otherwise secured beneath the outer edge portion of the member 35 and correspond in position to the plates 20. Each of the leaf springs 36 is notched at one edge as at 37 and is adapted 85 to interlock with a supporting spring member 38 similarly notched for this purpose as at 39. The notches in one set of coating spring members 36 and 38 are preferably reversed to prevent longitudinal movement of 90 the contact member 35.

An angle bracket 40 is secured to one of the flanges 21 by the bolt 22 thereof and includes an upstanding arm to which the lower end of the corresponding spring member 38 is riveted, as at 42. An adjusting screw 43, provided with a lock nut 44, extends through the upper end of each bracket arm 41 and bears against the corresponding spring member 38 to adjust the tension thereof. 95

The operation of the device is as follows:

As previously stated, it is advantageous to elevate the cloth at the point of weaving, but in previous attempts to accomplish the desired result, it has been possible to only 105 slightly elevate the cloth due to the cutting action of the wires against the elevating means, and the consequent abrasive action of the damaged elevating means against the wires. With the present device, it has been found that the free edge of the elevating member 35 can be brought up to the last shute wire, and can be elevated to a greater extent due to its novel construction.

In this connection it will be noted that the 110 resiliency of the member 35, and particularly the overhanging edge thereof, and the use of the resilient supporting members 38, materially reduces the cutting or abrasive action against the member 35, and this result is 115 greatly enhanced by the fact that the mounting of the device permits an elevating member of substantial area to be employed. In 120 actual practice, therefore, it has been found that the wearing action against the member 35 is negligible.

The slay 13 and the reed 16' operate in the usual manner to drive the shute wire into position, and this action causes the woven cloth to move suddenly forwardly and to momen- 125

tarily slightly slacken the cloth. The cloth adjacent the last shute wire is maintained elevated by the resilient member 35, and thus the latter is subjected to appreciable pressure by the fabric. The movement of the slay, transmitted by the fabric, accordingly causes the entire assembly comprising the members 35, 36 and 38 to move forwardly with the cloth, and then to return to normal position during the momentary slackening thereof, the return movement of the assembly being due to the resiliency of the members 38 and causing the edge of the member 35 adjacent the reed to extend over one additional shute wire. The reed directly strikes the member 35 only when the take-up is not properly adjusted and the release is greater than the amount of cloth woven, but no harm will be done under such conditions because of the freedom of movement of the member 35 and associated elements. The extension of the member 35 to the point of weaving also is made possible by the resilient mounting, the entire assembly referred to being free to move in the manner stated. Moreover, the resiliency of the device also permits the abrasive action of the wires against the member 35 to be reduced to a negligible point and prevents any irregularity in the cloth from striking the member 35, and breaking it as would occur if this member were stationary.

Only a slight tensioning of the device is required, and this tension readily may be adjusted by proper operation of the set screws 43. The adjustment of the set screws 43 obviously determines the limit of movement of the member 35 toward the reed. The lock nuts 44 obviously prevent any change in the adjustment of the resilient members of the device. The proper height of the elements may be secured by use of the proper shims 24.

The use of flexible material in the member 35 permits the upper face of the latter to contact throughout its width with the under side of the cloth to further reduce abrasion due to the large bearing surface provided. Moreover, the use of thin material in the member 35 allows the cloth to be woven near the bottom of the reed, which is its strongest point.

In view of the foregoing it will be apparent that the present device provides novel means for permitting the use of a standard wire weaving loom in the production of wire cloth which is perfectly flat and smooth. The device also permits the cloth to be made with materially heavier shute wires than has been accomplished with any prior constructions. Such a cloth, as previously stated, has material advantages when used in connection with paper making machines.

It is to be understood that the form of the invention herewith shown and described is to be taken as a preferred example of the same and that various changes in the shape, size

and arrangement of parts may be resorted to without departing from the spirit of the invention or the scope of the subjoined claims.

I claim:

1. In a wire weaving loom having a slay adapted to drive each filler wire into woven relation with warp wires, a relatively stationary member having its upper face arranged slightly above the normal plane of the woven cloth and engageable therewith to elevate it adjacent the weaving point where the slay moves to operative position to drive each filler wire into woven relation with the warp wires.

2. In a wire weaving loom having a slay adapted to drive each filler wire into woven relation with the warp wires, a resilient relatively stationary member having its upper face arranged slightly above the normal plane of the woven cloth and engageable therewith to elevate it adjacent the weaving point where the slay moves to operative position to drive each filler wire into woven relation with the warp wires, said resilient member being adapted to flex downwardly at least one edge portion.

3. In a wire weaving loom having a slay adapted to drive each filler wire into woven relation with the warp wires, a resilient relatively stationary member having its upper face arranged slightly above the normal plane of the woven cloth and engageable therewith to elevate it adjacent the weaving point where the slay moves to operative position to drive each filler wire into woven relation with the warp wires, and means for adjusting the resilient member toward the slay.

4. In a wire weaving loom having a slay adapted to drive each filler wire into woven relation with the warp wires, an elongated stationary plate arranged parallel to the slay, a resilient member supported on said plate with its upper face arranged slightly above the normal plane of the woven cloth, one edge of said resilient member extending beyond said plate and engageable beneath the cloth to elevate it adjacent the weaving point where the slay moves to operative position to drive each filler wire into woven relation with the warp wires.

5. In a wire weaving loom having a slay adapted to drive each filler wire into woven relation with the warp wires, an elongated stationary plate arranged parallel to the slay, a resilient member supported on said plate with its upper face arranged slightly above the normal plane of the woven cloth, one edge of said resilient member extending beyond said plate and engageable beneath the cloth to elevate it adjacent the weaving point where the slay moves to operative position to drive each filler wire into woven relation with the warp wires, and means for varying the distance of the projecting portion of said re-

- silient member from the slay when the latter is in operative position.
6. Apparatus constructed in accordance with claim 5 provided with a support for said plate, said tension varying means comprising a connection between said support and said resilient member, and an adjusting screw operating against said connection.
7. In a wire weaving loom having a slay adapted to drive each filler wire into woven relation with the warp wires, a plurality of stationary supports arranged in a line parallel to the slay, an elongated plate arranged over said supports and supported thereby in parallel relation to the slay, and a resilient member supported by said plate with its upper edge arranged slightly above the normal plane of the woven cloth, one edge of said resilient member extending beyond said plate and engageable beneath the cloth to elevate it adjacent the weaving point where the slay moves to operative position to drive each filler wire into woven relation with the warp wires.
8. Apparatus constructed in accordance with claim 7 provided with a resilient connection between said resilient member and each of said supports and exerting an inwardly moving tendency upon said resilient member.
9. Apparatus constructed in accordance with claim 7 provided with a bracket carried by each support, a resilient connection between said resilient member and each of said brackets and transmitting an inwardly moving tendency to said resilient member, and an adjusting screw threaded in each bracket and contacting with the corresponding resilient connection to vary the distance of said resilient member from the slay when the latter is in operative position.
10. Apparatus constructed in accordance with claim 7 wherein said plate supports said resilient member intermediate its longitudinal edges to permit both of the latter to flex downwardly.
11. In a wire weaving loom having a slay adapted to drive each filler wire into woven relation with the warp wires, and a breast beam over which the woven cloth is adapted to pass, a relatively stationary member carried by the breast beam and having its upper face arranged slightly above the normal plane of the woven cloth and engageable therewith to elevate it adjacent the weaving point where the slay moves to operative position to drive each filler wire into woven relation with the warp wires.
12. In a wire weaving loom having a slay adapted to drive each filler wire into woven relation with the warp wires, and a breast beam over which the woven cloth is adapted to pass, a transversely resilient elongated relatively stationary member carried by the breast beam parallel to the slay and having its upper face arranged slightly above the normal plane of the woven cloth and engageable therewith to elevate it adjacent the weaving point where the slay moves to operative position to drive each filler wire into woven relation with the warp wires.
13. Apparatus constructed in accordance with claim 12 provided with a rigid plate contacting with and supporting said resilient member intermediate its longitudinal edges whereby said member is adapted to flex downwardly at both of said edges.
14. Apparatus constructed in accordance with claim 12 provided with a rigid plate contacting with and supporting said resilient member intermediate its longitudinal edges whereby both of such edges are adapted to flex downwardly, and resilient means tending to urge said resilient member inwardly.
15. The combination with a wire weaving loom having a slay adapted to drive each filler wire into woven relation with the warp wires, of a relatively stationary member having its upper face arranged slightly above the normal plane of the woven cloth and engageable therewith to elevate it adjacent the weaving point where the slay moves to operative position to drive each filler wire into woven relation with the warp wires.
16. The combination with a wire weaving loom having a slay adapted to drive each filler wire into woven relation with the warp wires, of a resilient elongated relatively stationary member parallel to the slay and having its upper face arranged slightly above the normal plane of the woven cloth and engageable therewith to elevate it adjacent the weaving point where the slay moves to operative position to drive each filler wire into woven relation with the warp wires.
17. The combination set forth in claim 16 provided with a stationary member engageable with and adapted to support said resilient member intermediate the longitudinal edges thereof to permit such edges to flex downwardly.
18. The combination set forth in claim 16 provided with a stationary member engageable with and adapted to support said resilient member intermediate the longitudinal edges thereof to permit such edges to flex downwardly, and resilient means tending to urge said resilient member inwardly.
19. The combination with a wire weaving loom having a slay adapted to drive each filler wire into woven relation with the warp wires, and a breast beam over which the woven cloth is adapted to pass, of a relatively stationary member carried by the breast beam and having its upper face arranged slightly above the normal plane of the woven cloth and engageable therewith to elevate it adjacent the weaving point where the slay moves to operative position to drive each filler wire into woven relation with the warp wires.

20. The combination with a wire weaving loom having a slay adapted to drive each filler wire into woven relation with the warp wires, and a breast beam over which the woven cloth is adapted to pass, of an elongated relatively stationary resilient member carried by the breast beam parallel to the slay and having its upper face arranged slightly above the normal plane of the woven cloth and engageable therewith to elevate it adjacent the weaving point where the slay moves to operative position to drive each filler wire into woven relation with the warp wires, and an elongated stationary member carried by 15 breast beam and contacting with the lower face of said resilient member intermediate the longitudinal edges thereof to permit such edges to flex downwardly.

In testimony whereof I affix my signature.
